UNITED STATES PATENT OFFICE

147,722

DESIGN FOR A LAMP OR SIMILAR ARTICLE

Walter Fanelli, South Euclid, Ohio, assignor to Faries Manufacturing Company, Decatur, Ill.,
a corporation of Illinois

Application May 17, 1946, Serial No. 129,777

Term of patent 3½ years

(Cl. D48—20)

To all whom it may concern:

Be it known that I, Walter Fanelli, a citizen of the United States and a resident of the village of South Euclid, in the county of Cuyahoga and State of Ohio, have invented a new, original, and ornamental Design for a Lamp or Similar Article, of which the following is a specification, reference being had to the accompanying drawing, forming a part thereof.

On the drawing:

of Figure 2, showing the lamp base and defining the structure of the lamp standard.

I claim:

The ornamental design for a lamp or similar article, as shown.

WALTER FANELLI.
